UNITED STATES PATENT OFFICE.

DERWIN W. BOWIE, OF WOODRIDGE, NEW JERSEY, ASSIGNOR, BY MESNE ASSIGNMENTS, TO UNITED SHOE MACHINERY CORPORATION, OF PATERSON, NEW JERSEY, A CORPORATION OF NEW JERSEY.

HEEL-SEAT-FITTING MACHINE.

Application filed August 24, 1917. Serial No. 188,003.

To all whom it may concern:

Be it known that I, DERWIN W. BOWIE, a citizen of the United States, residing at Woodridge, in the county of Bergen and 5 State of New Jersey, have invented certain Improvements in Heel-Seat-Fitting Machines, of which the following description, in connection with the accompanying drawings, is a specification, like reference characters on the drawings indicating like parts in the several figures.

This invention relates to a machine for shaping the heel end of a sole to prepare it to receive the heel which is to be attached.

15 In the manufacture of shoes having leather heels it is customary to attach the rough heel, then to trim the heel and the edge of the heel portion of the sole simultaneously and later to scour and burnish 20 them. With wooden heels, this procedure has not been found to be practicable since to trim a wooden heel and the edge of a leather sole simultaneously in a satisfactory manner is difficult if not impossible. More- 25 over a wooden heel is commonly covered with a thin veneer of leather which can not be subjected to the scouring operation without injury. Accordingly it is the practice to finish wooden heels completely before they 30 are attached and to trim off the edge of the heel portion of the sole of the shoe so as to permit the upper edge of the heel to extend close to the upper of the shoe.

These wooden heels have a cavity in their 35 upper face; and the trimming of the heel portion of the sole should be such as to provide a seat to receive this cavity. Hitherto this operation has been performed by hand or by machines like that of United 40 States Letters Patent No. 1,307,285, granted June 17, 1919, on an application filed Sept. 14, 1915, in which the work is held stationary while traveling cutters form the heel-seat, such machines having proved accurate and 45 satisfactory.

A general object of the present invention is to provide a simpler machine for use in forming heel-seats. To this end one feature of the invention comprises a cutter and 50 means for relatively guiding the work and the cutter to cause the cutter to traverse the periphery of the heel end of the sole to remove waste stock therefrom in such a manner as to form a generally convex seat.

In the illustrative machine the shoe with 55 the sole attached is supported, guided and turned by hand, this operation being facilitated by a novel gage or other guiding member while a rotary cutter removes a horse-shoe-shaped portion from the margin of the 60 heel part of the sole to form a seat for the heel.

This and other features of the invention, including the form of the gage and other details of construction and combinations of 65 parts, will be described as embodied in an illustrative machine and will be pointed out in the appended claims.

Referring now to the accompanying drawings,—

70 Fig. 1 is an end elevation of a machine in which the present invention is embodied; Fig. 2 is a front elevation of the machine;

Fig. 3 is a perspective of a portion of a shoe showing the heel seat which is formed 75 by the beveled cutter, and

Fig. 4 is a similar perspective showing the offsets which are formed by the milling cutters.

80 Rotatably mounted in bearings in the frame of the machine are two shafts 5 and 7, the shaft 5 being driven by a belt 9 and the shaft 7 being driven from the shaft 5 by a belt 11. Fast to the end of the shaft 5 is an end cutter 13; herein shown as of 85 frusto-conical shape, and co-operating with this cutter is a guiding member 17 herein shown as a gage or rest the purpose of which is to facilitate relatively guiding and turning the work and the cutter 13. The 90 gage 17 comprises a narrow plate having a beveled lower end adapted to enter the rand crease of a shoe and provided at its upper end with a transverse slot 19 to receive a disk 21 carried at the lower end of an adjusting screw 23. A screw bolt 25, which passes through a slot in the gage and is threaded into the arm 27 which carries the thumb screw 23, serves to hold the gage firmly 95 in adjusted position. The arm 27 is pivoted 100 to the frame of the machine at 29 and is held upright, as shown, by a latch 31, the purpose of this construction being to permit the gage to be swung out of the way in order to facilitate removal and replacement 105 of the cutter 13.

The illustrative machine is designed to operate upon the sole after it has been at-

tached to the shoe; and in the operation of the machine, as thus far described, the rand crease is presented to the gage 17 at one end of the line where the breast of the heel 5 when attached will join the sole. The shoe is then moved along and turned until the opposite end of the line of the heel breast has been reached. During this moving and turning the cutter 13 removes stock in a 10 horseshoe-shaped area from the heel portion of the sole with the result illustrated in Fig. 3. In Fig. 1 one of the positions occupied by the shoe during the cutting operation is indicated in dotted lines. It 15 should be noted that the cut extends from substantially the line of junction of the upper with the sole to a line located a sufficient distance inside said line of junction to provide a beveled seat for the heel which 20 is to be attached.

It is usually desirable to produce sharp offsets or shoulders at the ends of the horse-shoe-shaped cut to provide abutments for the upper forward corners of a wooden heel. 25 To this end there are mounted on the shaft one at each end, milling cutters 33, and adjacent to each milling cutter is a gage or rest 35. The purpose of providing two milling cutters is first to cause the cutting to 30 be done from the outside in toward the middle portion of the sole and second to provide space for the fore-part of the shoe during the cutting operation. It is obvious, however, that a single cutter could be used 35 for cutting both shoulders if desired instead of using two cutters, one for the right and one for the left side as shown. The gages 35 are vertically adjustable by means of thumb screws 37 in sockets in the two ap- 40 proximately upright arms of a forked bell crank lever 39 which is pivoted to the frame of the machine at 41 and is normally held up by a spring 43 but may be pulled down so as to turn it in a counter-clockwise 45 direction about the pivot 41 by depressing a treadle (not shown) which is attached to the lower end of the treadle rod 45. The clockwise movement of the bell crank lever 39 is limited by contact of the lower arm 50 of the lever with the frame of the machine; and this extreme position is its normal position due to the action of the spring 43. After the seat has been formed as illustrated in Fig. 3, if it is desired to produce 55 the shoulders illustrated in Fig. 4, the shoe is presented, as indicated in dotted lines in Figs. 1 and 2, first to one milling cutter and then to the other, the treadle being manipulated to position the gages so that cuts 60 of the desired depth will be made.

The above-described shoulder-cutting means is not claimed herein, as it forms the subject-matter of my divisional application Serial No. 572,417, filed July 3, 1922.

65 Although the invention has been set forth

as embodied in a particular machine, it should be understood that the invention is not limited in the scope of its application to the particular machine which has been shown and described. -

70

Having thus described my invention, what I claim as new and desire to secure by Letters Patent of the United States is:

1. A machine for shaping the heel end of a sole attached to a shoe to prepare it to receive a heel, having, in combination, a cutter, means for guiding a sole to bring the edge and the tread face of its heel end progressively into the path of the cutter, and means for operating the cutter to form on said edge and tread face a seat to receive the cavity in the top of the heel which is to be attached.

75

2. A machine for shaping the heel end of a sole to prepare it to receive a heel, having in combination, a cutter adapted to operate upon the under or tread surface of the sole, and means, including a guide adapted to engage the upper surface of the sole, for facilitating guiding a sole to the cutter in such manner as to form on the heel end thereof a beveled seat the outer edge 90 of the major portion of the bevel of which extends from a point offset inwardly from the edge of the shank portion of the sole at 95 one side of the sole to a point similarly offset from the edge of the shank on the other side.

90

3. A machine for shaping the heel end of a sole to prepare it to receive a heel, having, in combination, means for facilitating guiding and turning a shoe with its attached sole, and means for removing stock in a horseshoe-shaped area from the margin of the tread face of the heel portion of the sole in such manner as to form a seat to receive the cavity of the heel which is to be attached.

100

4. A machine for shaping the heel end of a sole to prepare it to receive a heel, having, in combination, means for facilitating guiding and turning a shoe with its attached sole, and a cutter, constructed and arranged to bevel the margin of the heel end of the sole by a cut which extends substantially 110 from the line of junction of the upper with the sole to a line located a sufficient distance inside the line of said junction to provide a seat to receive the cavity formed in the top of the heel which is to be attached.

115

5. A machine for shaping the heel end of a sole to prepare it to receive a wooden heel, having, in combination, a gage adapted to engage the upper of the shoe to which the sole is attached and to permit the shoe to be swung while it is moved along in contact with the gage from the end of the line of the heel breast on one side around to the opposite end of the line of the heel 125 130

- breast, a cutter, and means for operating the cutter to form progressively around the heel end of the sole a seat to receive the cavity formed in the top of a wooden heel 5 which is to be attached.
6. A machine for shaping the heel end of a sole to prepare it to receive a wooden heel, having, in combination, a gage adapted to engage the upper of the shoe to which 10 the sole is attached and to permit the shoe to be swung while it is moved along in contact with the gage from the end of the line of the heel breast on one side around to the opposite end of the line of the heel breast, 15 a cutter, and means for causing the cutter to bevel the margin of the heel end of the sole by a cut which extends from the junction of the upper with the sole to a horse-shoe-shaped line inside the line of said junction. 20
7. A machine for shaping the heel end of a sole to prepare it to receive a wooden heel, having, in combination, a gage adapted to engage the rand crease of the shoe to 25 which the sole is attached and to permit the operator to swing the shoe while moving it along in contact with the gage from the line of the heel breast on one side around the heel end of the sole to the opposite end 30 of the heel breast line, and a cutter located adjacent to the gage, the shape of the cutter and its location with respect to the gage being such that a horseshoe-shaped portion is removed from the margin of the heel part 35 of the sole to form a seat to fit the cavity of a wooden heel.
8. A heel seat fitting machine having, in combination, a cutter, and means for guiding a sole to bring the edge and tread face 40 of its heel end progressively into the path of the cutter to remove waste material to form on said edge and tread face a beveled surface to form, with a transverse shoulder portion formed in any desired manner at 45 the breast line, a seat to receive the cavity in the top of a wood heel which is to be attached.
9. In a heel-seat-fitting machine, in combination, a gage for facilitating guiding 50 and turning a shoe to which the sole is attached, and means for removing stock in a horse-shoe-shaped portion from the margin of the tread face of the heel portion of the sole in such a manner as to form a beveled 55 seat to receive the cavity in the heel which is to be attached.
10. A machine for operating upon the sole of a shoe prior to the attaching of the heel, having, in combination, a gage or rest for 60 facilitating guiding and turning the shoe to which the sole is attached, a rotary cutter, and means for operating said cutter to remove a horseshoe-shaped portion from the margin of the tread face of the heel part of 65 the sole in such manner as to form a beveled
- seat to receive the cavity of the heel which is to be attached.
11. A heel-seat-fitting machine having, in combination, a gage for facilitating guiding and turning a shoe to which the sole is attached, a rotary cutter, and means for operating said cutter to remove a horse-shoe-shaped portion from the margin of the tread face of the heel part of the sole in such manner as to form a beveled seat to receive the cavity of the heel which is to be attached. 70
12. A heel-seat fitting machine having, in combination, a gage for facilitating guiding and turning a shoe to which the sole is attached, and a frusto conical end cutter adapted to remove a horse-shoe-shaped portion from the heel part of the sole of a shoe guided thereby. 75
13. A machine for beveling the rear end 80 of an outsole attached to a lasted shoe, to trim the sole to fit the seat concavity of a superposed wood heel as described, comprising, in combination, a power-operated frusto-conical end-milling cutter, and means for relatively guiding a shoe and the cutter to cause the cutter progressively to traverse the periphery of the heel end of the sole from the breast line on one side to the breast line on the other, to bevel the sole 85 to form a generally convex seat surface. 90
14. A machine for beveling the rear end of an outsole attached to a lasted shoe, to trim the sole to fit the seat concavity of a superposed wood heel as described, comprising, in combination, a cutter, and means for 100 relatively guiding a shoe and the cutter to cause the cutter progressively to traverse the periphery of the heel end of the sole from the breast line on one side to the breast line on the other, to bevel the sole to form a generally convex seat surface. 105
15. A machine for operating on shoes comprising, in combination, a tool for operating on a shoe adjacent the rand crease, a gage member extending across said tool to enter the rand crease of a shoe operated on by the tool to guide it, and a pivoted arm carrying said gage member constructed and arranged alternatively to hold it in guiding 110 position or in an idle position permitting access to the tool. 115
16. A machine for operating on shoes comprising, in combination, a tool for operating on a shoe adjacent the rand crease, a gage member extending across the tool into a position to enter the rand crease of a shoe operated on thereby, a pivoted arm carrying a gage member, and a latch to hold said arm in operative position and arranged to 120 be disengaged to allow the arm to be turned to an inoperative position. 125

In testimony whereof I have signed my name to this specification.

DERWIN W. BOWIE.
